UNITED STATES PATENT OFFICE.

ADOLPH OLEVIN, OF DETROIT, MICHIGAN, ASSIGNOR TO MERIDIAN MACHINE PRODUCTS CORPORATION, OF DETROIT, MICHIGAN, A CORPORATION OF MICHIGAN.

MICROMETER-CALIPERS.

1,310,431.

Specification of Letters Patent. Patented July 22, 1919.

Application filed May 1, 1918. Serial No. 231,927.

To all whom it may concern:

Be it known that I, ADOLPH OLEVIN, a citizen of the United States, residing at Detroit, in the county of Wayne and State 5 of Michigan, have invented certain new and useful Improvements in Micrometer-Calipers; and I do hereby declare the following to be a full, clear, and exact description of the invention, such as will enable others 10 skilled in the art to which it appertains to make and use the same.

This invention comprehends generally improvements in that class of inventions known as measuring instruments and more 15 particularly relates to micrometer calipers.

It is the principal aim and object of the present invention to provide a device of the above mentioned character designed to operate in the nature of a micrometer for accurately determining the thickness of a piece 20 of work, while the several parts are of a novel form to insure of an effective adjustment of the device when desired.

It is an equally important object of this 25 invention to provide a device of the above mentioned character wherein improved means is mounted in and adjustable with the movable jaw for obtaining a fine adjustment of the movable jaw with respect to the stationary jaw.

More particularly this invention contemplates the provision of a device of the above mentioned character wherein improved manually operable means is provided for normally holding the movable jaw adjusting means in operable relation with the main shank yet such means is actuatable at times to permit of a quick sliding adjustment of the movable jaw.

40 It is a further object of this invention to provide a device of the above mentioned character which is simple in construction, thoroughly reliable and efficient in its purpose and inexpensive in manufacture.

45 Other objects will be in part obvious and in part hereinafter set forth.

The invention accordingly consists in the features of construction, the combination of

elements and the arrangement of parts which will be exemplified in the construction hereinafter described and the scope of the application of which will be indicated in the appended claims.

The invention is clearly illustrated in the accompanying drawing, in which:—

Figure 1 is a side elevation of the improved device.

Fig. 2 is an enlarged longitudinal sectional detail view of the movable jaw and its adjusting means.

Fig. 3 is a section taken on line 3—3 of Fig. 2 in the direction in which the arrows point.

Fig. 4 is a section taken on line 4—4 of Fig. 2 in the direction in which the arrows point.

Similar characters of reference are employed in all of the above described views, to indicate corresponding parts.

Referring now, more particularly, to the accompanying drawing there is provided a shank 1 which has marked on one side face a plurality of graduations while the inner edge of this shank is formed with a plurality of threads or worm teeth 2 running for instance forty to the inch. A rigid jaw 3 is formed on one end of the shank and cooperating with this rigid jaw is a movable jaw 4, the body of which is slidable upon the shank.

With a view toward providing the improved means for adjusting the movable jaw relative to the stationary jaw, a substantially U-shaped frame 5 is disposed within the open body of the jaw 4 while the side arms of the frame are bifurcated as at 6 and disposed on opposite sides of the shank 1. A pintle 7 is journaled through the arms of the frame and has the respective ends projecting through and operating in opposed slots 8 in the body of the jaw 4, these slots permitting of movement of the frame toward and from the shank in a manner and for a purpose that will hereinafter become apparent. A cylindrical barrel or roller 9 is rigidly connected to the pintle and is

positioned between the arms of the frame 5 and is formed on its outer periphery or surface with a plurality of threads 10 running about forty to the inch and corresponding of course to the threads or worm teeth 2 on the shank 1. A wheel or head 11 is carried on the inner end of the pintle, being accommodated within a recess 12 in the engaging face of the movable jaw 4, and this head or wheel 10 is provided in its periphery with twenty-five graduation marks or lines indicated by the numeral 13 for obtaining a fine adjustment of the movable jaw in a manner that will hereinafter become apparent. For a 15 like purpose a similarly graduated disk 14 is carried by the opposite projecting end of the pintle 7.

If desired the barrel 9 may be knurled to permit the same to be readily grasped and 20 turned when the head 11 of pintle 7 is not readily accessible, though I do not deem this necessary under ordinary conditions.

In order to normally hold the barrel or roller 9 in operable relation with the threaded shank 2, yet at the same time act as a 25 means for adjusting the frame so as to consequently permit of a quick sliding adjustment of the movable jaw on the shank, a set screw is employed and consists of a threaded shank 15 formed with a knurled head 16, the shank being adjustable through a correspondingly threaded opening 17 in the movable jaw and having its inner end swiveled as at 18 in the intermediate portion of the frame. By this arrangement it is apparent 30 that by rotating the head 16, the frame 5 will be drawn away from the shank and toward the adjacent end of the opening in the body of the movable jaw so as to consequently remove the threads 10 on the barrel or roller from engagement with said teeth 2 on the shank, thus enabling the user to 35 quickly and conveniently slide the movable jaw on the shank and subsequently of course it is only necessary to tighten the screw so as to replace the barrel or roller in engagement with the threaded shank.

In use, assuming that the parts have been assembled in the manner described and as 50 illustrated in the drawing, to measure the thickness of a piece of work (not shown) which for instance may be approximately two inches, the set screw 15 is loosened so as to permit of the sliding of the movable jaw 4 so that the engaging face of this jaw registers with the two inch mark. Subsequently the screw is tightened to arrange the threaded barrel 10 in engagement with the threaded shank 2. Now by adjusting either the 55 graduated head 11 or the correspondingly graduated disk 14 the distance between two of the adjacent graduations 13 thereon with respect to the center part 17, the barrel will be adjusted one one-thousandth of an inch,

as the threads on the shank 1 and barrel 9 65 are so related as to cause movement of the slideable jaw through the distance of one-fortieth of an inch for each complete rotation of the same. It will therefore be seen that a very fine adjustment may be made 70 with this particular construction.

It is believed in view of the foregoing description that a further detailed description of the operation of the invention is entirely unnecessary. Likewise, it is believed that 75 the advantages of the invention will be readily apparent.

As many changes could be made in the above construction and many apparently widely different embodiments of this invention could be made without departing from the scope thereof it is intended that all matter contained in the above description or shown in the accompanying drawing shall be interpreted as illustrative and not in a 85 limited sense. It is also to be understood that the language used in the following claims is intended to cover all the generic and specific features of the invention therein described and all statements of the scope of 90 the invention which as a matter of language might be said to fall therebetween.

Having thus fully described the invention, what is claimed as new and desired to be secured by Letters Patent is:

1. A device of the character described including, a shank having notches in one edge thereof, a rigid jaw carried by one end of the shank, a second jaw slideable on the shank, a frame slidably mounted in the movable jaw and having bifurcated end bars straddling said shank, a pin journaled through the frame and having its respective ends slideable in the second named jaw, a barrel carried by the pin and provided with threads coöperating with the notches in the shank, a graduated adjusting head carried by the pin for rotatably adjusting the barrel, and means for removably holding the threaded barrel in engagement with the 110 threads on the shank.

2. In a device of the character described, a shank having notches in one edge thereof and provided with a jaw at one end, a slideable jaw arranged on said shank, a substantially U-shaped frame slidably mounted in the body of said slideable jaw for movement toward and away from the shank, said U-shaped frame having bifurcated side bars adapted to fit snugly about the shank adjacent the notched edge thereof and guide the frame during movement toward and away from said shank, a pintle rotatably carried by the side bars of the U-shaped frame and projecting therebeyond, said slideable jaw being provided with slots to accommodate the end portions of the pintle and to permit movement of the slideable frame toward and

away from the shank, a barrel mounted on the pintle and having threads coöoperating with the notches in the shank for adjusting the slidable jaw, means for adjusting said 5 slidable frame toward and away from the shank so to bring the threads of the shank into or out of engagement with the notches of the shank, and graduated members secured to the ends of said pintle for indicat-

ing the rotary adjustment of the barrel 10 through a predetermined distance.

In testimony whereof I affix my signature in presence of two witnesses.

ADOLPH OLEVIN.
